UNITED STATES PATENT OFFICE.

JOHN W. SHULTS, OF WICHITA, KANSAS.

GALVANIC BODY-BATTERY.

SPECIFICATION forming part of Letters Patent No. 486,902, dated November 29, 1892.

Application filed March 22, 1892. Serial No. 425,982. (No model.)

To all whom it may concern:

Be it known that I, JOHN W. SHULTS, a citizen of the United States of America, residing at Wichita, in the county of Sedgwick and 5 State of Kansas, have invented certain new and useful Improvements in Galvanic Electric Batteries, of which the following is a specification, reference being had therein to the accompanying drawings, and the letters of reference thereon, forming a part of this specification, in which—

Figures 1 and 2 are face views of the battery; Fig. 3, a back view of the same, also showing a supporting-cord and the conductors of the battery; Fig. 4, a longitudinal sectional view of the battery on line 2 2 of Figs. 2 and 3; Fig. 5, a cross-sectional view of the same on line 1 1 of Figs. 2 and 3; Fig. 6, an enlarged sectional view of one end portion of the battery on the same line as that of Fig. 4; Fig. 7, a detailed side view of the cap or cover for inclosing the receptacle of the body portion of the battery, a portion thereof being shown in section to disclose its hollowed 5 form; and Figs. 8 and 9 are detailed perspectives of the metallic elements of the battery.

This invention relates to certain improvements in galvanic electric batteries of a class 5 designed as a body-battery to be worn in contact with the body of a person in such manner that the elements thereof will be subjected to the exudations out of the cutis; and it consists of a body portion of vulcanized rubber having set therein or fixed thereon metallic elements or two or more cells of an electric battery; of electric conductors connected with and extending from the poles of the battery, which terminate with electrodes adapted 5 to be held in contact with the body of the wearer, and of a receptacle made in the battery-body for holding a deposit of muriate of ammonia or other preparation or compound suitable as an element for generating an electric current, which is adapted to sift through 5 perforations of the receptacle and come in contact with the body of the wearer, which improvements are fully set forth and explained in the following specification and pointed out in the claims.

Referring to the drawings, D represents the body portion of the battery, and is shown

as having face depressions, into which the metallic elements, which are of thin sheet metal, and shown at a a' and d d', are set, said elements being respectively provided with extending prongs Z, as shown in Figs. 8 and 9, and in setting said elements holes are bored or otherwise made, corresponding with said prongs, into the body portion D, leading from 55 said face depressions at an angle, as shown at Z' in Fig. 6, and said prongs Z are forced into said holes, and without again bending said prongs the elements cannot be removed if their body portion is not disturbed. The 60 elements d d' are further provided with a broader prong e opposite the prong Z, (see Fig. 9,) which prong e of each said element is bent at right angle to the element-body and placed into a corresponding recess 65 of the body D, as shown in Figs. 4 and 6, which is adjacent a screw-hole at each element, and into said screw-holes are respectively turned the screws w w', which come in contact with and hold the prongs e, and c 70 c' represent the conductors of the battery, which are preferably of cord, having metallic strands interwoven or twisted with fibrous material, and are electrically connected with the battery elements d d', through the agency 75 of the screws w w', by being held clamped under the heads of said screws, as shown in Figs. 3, 4, and 6, and terminate with metallic-button electrodes G G', electrically connected therewith, as shown in Fig. 3.

I have illustrated a battery incorporating two cells in which I prefer that the center elements of one cell be of copper, as at d, and the opposite like element be of zinc, as at d', each of circular form, and that their fellow-elements be of like metal, circular in form, with their center portion removed, and arranged encircling the center elements; arranging a copper element a about a zinc element d', and a zinc element a' about a copper element d, 90 and electrically connecting said elements a a', as shown at v in Fig. 1, or by removing a portion of each of said elements and abutting them, as shown in Fig. 2.

R represents a receptacle made as a chamber in the back of the body D to a depth nearly touching the line of seat of the metallic elements, as shown in Fig. 5, and in the bottom thereof is provided with one perforation on a

series of perforations, as shown at P, opening at the face of the battery adjacent the metallic elements, as shown in Figs. 1, 2, and 5, and D' is a cap or cover made with a flange to 5 closely fit into said receptacle to inclose it at the back of the battery, and within said receptacle is placed muriate of ammonia or other preparation or compound, as hereinbefore mentioned, which must be in a dry powdered form and may be triturated with some 10 substance to render it less potent to a degree to meet the requirements in special treatment, and when the battery is worn in contact with the body the said powder sifts through said 15 perforations and comes in contact with the body, and therefore in contact with the exudations out of the cutis and dissolves the greasy substances of said exudations, and 20 thereby moistening the powder and forming a liquid compound, which, like unto the exudations, being of an alkaline reaction when subjected to the metallic elements of the battery, assists the exudations in the generation of an electric current, and by means of the 25 conductors c c' and the body of the wearer between the contact-points of the electrodes a circuit is made, which results in the said electric current continuously passing through the body or extremities of the person wearing 30 the battery.

S S are screw-eyes turned into one side portion of body D of the battery, and have secured to them a supporting-cord S', as shown in Fig. 3, which serves as a means of support 35 for the battery by placing said cord about the wearer's neck or securing it about any portion of the body or extremities thereof.

The object of this invention is to construct 40 a portable body-battery for therapeutical purposes, wherein the exudations out of the cutis of the body of the wearer are utilized as an element of the battery, and wherein muriate of ammonia or its equivalent are utilized 45 as an assistant of the said exudations in generating an electric current, and also wherein the body or extremities of the wearer is made as a part of the electric circuit of the battery.

Having thus described my invention, what 50 I claim as new and useful, and desire to secure by Letters Patent, is as follows:

1. A galvanic electric battery consisting of a body portion of vulcanized rubber provided with a receptacle therein for holding an exciting material and with a perforation or perforations leading from the receptacle to the 55 face of said body portion, of metallic elements of an electric battery set in or fixed to said body portion, and of electric conductors arranged connected with the poles of the battery and terminating with electrodes, substantially as and for the purpose set forth.

2. A galvanic electric battery consisting of a body portion of vulcanized rubber provided with a receptacle therein and with one or more perforations leading from the receptacle 65 to the face of said body portion, of a deposit of muriate of ammonia or an equivalent exciting material or compound placed in said receptacle and adapted to sift through said perforations, of metallic elements of an electric battery set in or fixed to said body portion, and of electric conductors arranged connected with the poles of the battery and terminating with electrodes, substantially as and for the purpose set forth.

3. The herein-described galvanic electric battery, consisting of the body portion provided with a receptacle in the back thereof and with face perforations leading into said receptacle, of the cap or cover for inclosing 80 said receptacle, of the metallic elements set in the face of said body portion, of the conductors arranged electrically connected with said metallic elements and terminating with button electrodes, and of the battery-supporting cord connected with said body portion, wherein a deposit of muriate of ammonia or an equivalent exciting material substance or compound is placed in said receptacle and adapted to sift through the perforations leading therefrom, and wherein both the siftings of said deposit and the metallic elements of the battery are adapted to be brought in contact with the body of the wearer and the exudations out of the cutis, substantially as and for the purpose set forth.

JOHN W. SHULTS.
